[57] CLAIM

The ornamental design for a photographic camera, substantially as shown and described.

DESCRIPTION

FIG. 1 is a front elevational view of a photographic camera, showing our new design;
FIG. 2 is a rear elevational view thereof;
FIG. 3 is a top plan view thereof;
FIG. 4 is a bottom view thereof;
FIG. 5 is a right side elevational view thereof;
FIG. 6 is a left side elevational view thereof;
FIG. 7 is a front elevational view of a second embodiment thereof;
FIG. 8 is a rear elevational view thereof;
FIG. 9 is a top plan view thereof;
FIG. 10 is a bottom view thereof;
FIG. 11 is a right side elevational view thereof;
FIG. 12 is a left side elevational view thereof;
FIG. 13 is a front elevational view of a third embodiment thereof;
FIG. 14 is a rear elevational view thereof;
FIG. 15 is a top plan view thereof;
FIG. 16 is a bottom view thereof;
FIG. 17 is a right side elevational view thereof;
FIG. 18 is a left side elevational view thereof; and
FIG. 19 is an enlarged detail view of the portion of the surface ornamentation indicated by circle 19 in FIG. 1. The surface ornamentation indicated on the major portion of the body of the camera, in each embodiment thereof, and on the adjusting rings on the lens, is a multiplicity of small pyramids arranged in rows and projecting from the surface as is clearly shown in FIG. 19.
